DESIGN FOR A FORGING PRESS

William W. Criley, Cleveland, Ohio

Application July 8, 1938, Serial No. 78,343

Term of patent 7 years

To all whom it may concern:

Be it known that I, William W. Criley, a citizen of the United States and a resident of Cleveland, county of Cuyahoga and State of Ohio, have invented a new, original, and ornamental Design for a Forging Press, of which the following is a specification, reference being had to the accompanying drawings forming a part thereof.

The accompanying drawings comprise three

perspectives of a forging press embodying my new design, Fig. 1 being taken from the left front corner, Fig. 2 from the right front corner, and Fig. 3 from the right rear corner.

What I claim is:

The ornamental design for a forging press, as shown.

WILLIAM W. CRILEY.
